(57) **CLAIM**

The ornamental design for a combined banana-shaped toothbrush and teether for infants, as shown and described.

DESCRIPTION

FIG. 1 is a front perspective view of a combined banana-shaped toothbrush and teether for infants showing my design;

FIG. 2 is a reduced side view of FIG. 1;

FIG. 3 is the opposite side view of FIG. 2;

FIG. 4 is a front view of FIG. 2;

FIG. 5 is a rear view of FIG. 2;

FIG. 6 is a top view of FIG. 2; and,

FIG. 7 is a bottom view of FIG. 2.

None of the bristles, protrusions, ridges, or nubs, which are depicted in phantom, forms any part of the claimed design.
